UNITED STATES PATENT OFFICE.

WILLIAM N. BLAKEMAN, JR., OF NEW YORK, N. Y.

DRYING-OIL.

SPECIFICATION forming part of Letters Patent No. 767,682, dated August 16, 1904.

Application filed August 11, 1903. Serial No. 169,095. (No specimens.)

To all whom it may concern:

Be it known that I, WILLIAM N. BLAKEMAN, Jr., of the borough of Manhattan, in the city, county, and State of New York, have invented 5 a new and useful Drying-Oil, which invention is fully set forth in the following specification.

The object of this invention is to treat non-drying fatty oils in such a manner that drying properties will be imparted thereto, thus rendering them available for use for many purposes for which they are not now adapted.

The non-drying fatty oils which may be treated by my process are cotton-oil, sunflower-oil, corn-oil, castor-oil, and the like; and 15 my invention consists in incorporating with such oils a small percentage of tung-oil, known also as "Chinese" or "Japanese" wood-oil.

Tung-oil seems to be a very remarkable oleaginous product, the composition of which 20 is not now well understood, and although classed among the drying-oils the result of its induration is very different from the oxidized film of the well-known drying-oils, for when exposed to the atmosphere in a thin 25 layer on plain surfaces it dries to a rough, opaque, and arborescent film.

I have discovered that when about fifteen 30 per cent. of tung-oil is incorporated with one of the non-drying fatty oils—cotton-oil, for example—the compound or mixture will form a drying-oil possessing good drying qualities well adapted for use in the arts for many purposes.

In carrying out my process I simply take 35 the desired proportions of each oil and thoroughly incorporate one with the other. Either the tung-oil or the non-drying fatty oil, or both, may be oxidized before being combined, and a more energetic and complete blending 40 thus effected.

The tung-oil may be combined with a mixture of two or more of the non-drying oils. From five to ten per cent. of linseed or other drying oil, either raw or boiled, may be added as a drier, if desired, in which case the proportion of tung-oil may be slightly reduced. 45

The proportion of tung-oil which I use is from about ten per cent. as a minimum to twenty-five per cent. as a maximum, depending upon the nature of the non-drying oil used, fifteen per cent. giving satisfactory results in nearly every case.

In another application, Serial No. 169,096, filed herewith, I have claimed a paint compound made from the drying-oil herein described, in 55 combination with a pigment.

Having thus fully described my invention, I claim—

1. As a new composition of matter, a drying-oil composed of, substantially, eighty-five 60 parts of non-drying fatty oil and fifteen parts of tung-oil.

2. As a new composition of matter, a drying-oil composed of, substantially, eighty-five parts of cotton-oil and fifteen parts of tung- 65 oil.

3. As a new composition of matter, a drying-oil composed of tung-oil and an oxidized non-drying fatty oil.

4. As a new composition of matter, a drying-oil, composed of oxidized tung-oil and an oxidized non-drying fatty oil. 70

5. As a new composition of matter, a drying-oil composed of, substantially, eighty-five parts of non-drying fatty oil, fifteen parts of 75 tung-oil, and a drier.

WM. N. BLAKEMAN, JR.
